UNITED STATES PATENT OFFICE.

CLAUDE E. COX, OF DETROIT, MICHIGAN.

PISTON.

Application filed April 21, 1921. Serial No. 463,348.

To all whom it may concern:

Be it known that I, CLAUDE E. Cox, a citizen of the United States, residing at Detroit, in the county of Wayne and State of Michigan, have invented a new and useful Piston, of which the following is a specification.

The object of my invention is to provide a light weight piston for internal combustion engines, and an improved method of accurately finishing the same in such manner as to maintain great uniformity of cross-section of its skirt.

The accompanying drawings illustrate my invention: Fig. 1 is a side elevation; Fig. 2 is a section at right angles to the axis of the pitman pin; Fig. 3 is a side elevation at right angles to the plane of Fig. 1; Fig. 4 is an end elevation; Fig. 5 is a transverse section through the pitman pin; Fig. 6 is a diagram showing the manner of initial handling of the piston for the first machine operation; Fig. 7 is a diagram showing the manner of holding the piston for boring the pin bosses; and Fig. 8 is a diagram showing the manner of holding the piston for the external machining operations.

In the drawings 10 indicates the piston head provided with a cylindrical flange 11 of just sufficient length to permit the formation therein of adequate ring-grooves 12.

At diametrically opposite points the flange 11 is extended to form skirts 13, 13 each having an angular extent of approximately 90°. At each edge each skirt is stiffened by an inwardly extending flange 14 gradually increasing in width from the tip of the skirt to its junction with flange 11, but comparatively narrow. Internally, each skirt 11 is transversely stiffened by several narrow lateral arc-shaped ribs 15 and, at the lower edge of the skirt, by a rib 16. Ribs 15 and 16 join flanges 14.

The bosses 17, 17, for the pitman-pin are arranged between each pair of flanges 14 and approximately at the middle of the length of the piston and each boss is supported by a pair of diverging thin arms 18, 18 which merge into a flange 14 and flange 11 at a junction between such flanges 11 and 14. Each arm 18 is stiffened by an inner rib 19, which extends from boss 17 to flange 11, and an outer rib 20, which extends from boss 17 to the adjacent flange 14.

The inner face of head 11 is stiffened by

ribs 21 which need not be as wide as the depth of flange 11 if said flange is deep enough for two ring grooves, as shown. At the center, the head 11, on its inner face, is provided with a conical seat 22 to form a basis for the working center 24.

In order to machine this piston so as to insure uniform thickness of the skirts and flange 11, and thus make minimum thickness commercially possible, and also to compensate distortions due to release of internal stresses as external portions are removed, I have devised the following method of machining.

The rough castings, of any desired suitable metal, is chucked upon an internal chuck 30 which engages close to the cylindrical flange 11 and the skirts 13, and supporting the ends of said skirts. The ends of the skirts 13, including rib 16, are then carefully machined, preferably by at least a final grinding, to form accurately arc-shaped V ends 23, 23. The center 24 is also formed while the piston is held upon the internal chuck.

The piston is then clamped between a center pin 25, which enters center 24, and a head 26 provided with a circular V-shaped groove 27 with which ends 23 of skirts 13 will accurately fit. Thereupon bosses 17 are bored and reamed by tools carried by arbors 28.

The piston is then mounted in a finishing machine provided with a head 26' similar to head 26 and provided with a circular V-shaped groove 27', being clamped thereon by an internal clamping rod 29 carrying a pin 30 fitting the bores of bosses 17. The piston is further supported by the usual tail-stock pin 31 which enters center 24.

The usual turning and grinding operations for forming and finishing grooves 12 and the external surfaces of head 10, flange 11 and skirts 13 will be performed while the piston is supported in the manner shown in Fig. 8. By following the above described method the skirt walls and flange 11 may be made much thinner than has been heretofore considered practicable because no allowance has to be made for possible eccentricity of inner and outer walls. The free ends of the skirts being firmly held by the seating of the V-shaped ends 23 in the seat 27 and 27', it is apparent that the various machining operations can be carried on

with great rapidity without liability of distortion.

It will be noted that the triangles formed by head 10 and the two pairs of arms 18 provide a rigid structure for the transmission of the explosive forces to the pitman, while the side thrust of the pitman upon the skirts 13 is somewhat flexibly resisted owing to the fact that arms 18 join flanges 14 of skirts 13 only at their junction with flange 11. This construction affords a desirable flexibility in the skirts which insures against rupturing of the oil film upon which the skirts ride, and reduces piston-slap and resultant noise.

I claim as my invention:

1. An integral piston comprising a head, a comparatively short cylindrical ring-carrying flange, circumferentially separated arc-shaped skirts, cross-pin bosses, and two pairs of arms diverging at an angle less than 180 degrees connecting the cross pin bosses with the skirts at points between the head and the axis of the bosses.
2. An integral piston comprising a head, a comparatively short cylindrical ring-carrying flange, circumferentially separated arc-shaped skirts, transverse stiffening ribs on the inner faces of the skirts, cross-pin

bosses, and two pairs of arms diverging at 30 an angle less than 180 degrees connecting the cross pin bosses with the skirts at points between the head and the axis of the bosses.

3. An integral piston comprising a head, a comparatively short cylindrical ring-carrying flange, circumferentially separated arc-shaped skirts, having inturned narrow flanges at their edges, cross-pin bosses, and two pairs of angularly diverging arms connecting the cross-pin bosses with the in-turned flanges of the skirts at points between the head and the axis of the bosses, and transverse stiffening ribs on the inner faces of the skirts.

4. An integral piston comprising a head, 45 a comparatively short cylindrical ring-carrying flange, circumferentially separated arc-shaped skirts, having inturned narrow flanges at their edges, cross-pin bosses, and two pairs of angularly diverging arms connecting the cross-pin bosses with the in-turned flanges of the skirts at points between the head and the axis of the bosses.

In witness whereof, I have hereunto set my hand at Chicago, Ill., this 13th day of 55 April, A. D. one thousand nine hundred and twenty one.

CLAUDE E. COX.
